(57) **CLAIM**

The ornamental design for an LED component, as shown and described.

DESCRIPTION

FIG. 1 is a perspective view of one embodiment of an LED component showing our design;

FIG. 2 is a top plan view of the LED component shown in FIG. 1;

FIG. 3 is front elevation view of the LED component shown in FIG. 1;

FIG. 4 is a back elevation view of the LED component shown in FIG. 1;

FIG. 5 is a right side elevation view of the LED component shown in FIG. 1, with the left side elevation view being a mirror image thereof;

FIG. 6 is a perspective view of another embodiment of an LED component showing our design;

FIG. 7 is a top plan view of the LED component shown in FIG. 6;

FIG. 8 is front elevation view of the LED component shown in FIG. 6;

FIG. 9 is a back elevation view of the LED component shown in FIG. 6;

FIG. 10 is a right side elevation view of the LED component shown in FIG. 6, with the left side elevation view being a mirror image thereof;

FIG. 11 is a perspective view of another embodiment of an LED component showing our design;

FIG. 12 is a front elevation view of the LED component;

FIG. 13 is a back elevation view of the LED component;

FIG. 14 is a top plan view of the LED component;

FIG. 15 is a right side elevation view of the LED component, with the left side elevation view being a mirror image thereof;

FIG. 16 is a perspective view of still another embodiment of an LED component showing our new design;

FIG. 17 is a front elevation view of the LED component;

FIG. 18 is a back elevation view of the LED component;

FIG. 19 is a top plan view of the LED component; and, FIG. 20 is a right side elevation view of the LED component, with the left side elevation view being a mirror image thereof.

The broken lines shown in FIGS. 1-20 form no part of the claimed design in the different embodiments. The material forming the dome shaped features can be visually transparent or translucent, and in some embodiments can optically distort the features below.
